UNITED STATES PATENT OFFICE

WILLARD H. KEMPTON, OF WILKINSBURG, PENNSYLVANIA, ASSIGNOR TO WESTINGHOUSE ELECTRIC & MANUFACTURING COMPANY, A CORPORATION OF PENNSYLVANIA

STRAIN INSULATOR

Application filed April 6, 1927. Serial No. 181,326.

My invention relates to strain insulators, and particularly to strain insulators embodying interlinked metal parts.

One object of my invention is to provide an insulator of the above-indicated character that shall greatly facilitate its manufacture.

Another object of my invention is to provide a strain insulator that shall so resolve the strains into straight lines as to secure greater strength for a given amount and kind of material.

Another object of my invention is to provide a strain insulator that shall have no curved or other parts likely to become distorted under strain.

Another object of my invention is to provide a strain insulator, embodying an insulating shell or cover, that shall be so constructed as to avoid fracturing the shell under load conditions.

Another object of my invention is to provide a strain insulator that shall embody novel anchoring means for a molded insulating cover thereof.

25 A further object of my invention is to provide a strain insulator that shall be simple and durable in construction, economical to manufacture and effective in its operation.

In practicing my invention, I provide an insulator of such construction that certain of its parts may be suited to quantity production, by cutting them from bars; that permits ready assembly of its parts; that resolves its strains into straight lines to prevent fracture of its insulation and is otherwise constituted to be a material improvement over strain insulators heretofore employed and proposed.

40 Figure 1 of the accompanying drawings is an end view of a strain insulator constructed in accordance with my invention, parts being broken away and in section.

Fig. 2 is a side view of the device shown in Fig. 1,

45 Fig. 3 is a side view, partially in section and partially in elevation, of the structure shown in Figs. 1 and 2, taken at right angles to Fig. 2,

50 Figs. 4 and 5 are detail perspective views

of parts embodied in the insulator of the foregoing figures, and

Fig. 6 is a view, similar to Fig. 3, of a modified form of the invention.

Referring to Figs. 1 to 5, inclusive, the 55 insulator comprises, in general, rectangular or oblong block elements 2, terminal members 3, a loop or interlinking metal member 4 and a molded insulating cover member 5.

The block elements 2, together with the 60 terminal members 3, constitute terminal structures of substantially T-shape, or oppositely-projecting terminals having enlarged inner ends, in which the enlarged inner ends or heads are disposed in substantially parallel 65 relation and surrounded by the interlinking member 4 through which the legs of the T-structure extend.

As more clearly illustrated in Fig. 5, each 70 of the blocks 2 comprises a rectangular metal core or anchor member 7 and a substantially tubular insulating cover 8 that is preferably molded in position and constructed of laminations or layers of paper or other suitable sheet insulating material impregnated with a hard molding material. As thus constructed, the blocks 2 may be readily cut from relatively 75 long bars of the rectangular metal cores on which the molded insulating cover 8 has been placed.

Before or after cutting the above-mentioned bars, holes or openings 10 may be drilled and tapped for the reception of screw-threaded shank portions 11 of the terminal members 3.

80 The interlinking member 4 is of substantially tubular construction, whereby it may also be cut from greater lengths of such tubing, and is preferably of such rectangular cross-sectional area as to effect a neat sliding or press fit with two of the blocks 2.

The member 4 is further provided with oppositely disposed side openings 12 of appreciably larger diameter than the shanks 11 and has beveled edges 14 constituting holding or anchoring portions for assisting in holding the molded insulating body or cover 5 in position.

95 In constructing the insulator, the blocks 2 are pressed or passed through an end of the 100

interlinking member 4 to positions in which they are in flat-surface relation to each other and in which the screw-thread openings 10 register with the openings 12. The terminal members 3, or dummies therefor, are then screwed into the openings 10 through the openings 12.

After the above-mentioned operation, the structure is placed in a mold, and the insulating body or cover 5 is molded in position.

During the molding operation, the material of the body 5 is pressed into the spaces, in the openings 12, between the member 4 and the terminal members 3. Also, bosses 16 are formed in the cover having notches 17 therein that cooperate with the ends of pins 18, extending through the terminal members 3, to prevent turning, or unscrewing, of the shanks 11 from the blocks 2.

In the above-described structure, only the sides of the cores 7 are covered by the laminated insulating bodies 8, the ends of the core members and the entire insulator being covered by the insulating body 5. This feature provides insulation that is very strong mechanically and electrically, where such insulation is most needed, and a general effective insulating protection for the insulator in a simple, economical manner.

Also, in the above-described structure, the flat right-angular relation of the stressed parts eliminate the collapsing tendency of curved parts in strain devices of this character. This tendency results in fracture and dislocation of the parts, particularly of the insulation which is thereby very readily rendered unfit for service and causes breakdown of the insulator.

In my device, the insulating bodies 8 are substantially in straight compression, and the insulating cover 5 is practically free of mechanical stresses of any kind.

In the modification of my invention shown in Fig. 6, in which corresponding parts are designated by corresponding reference characters, the construction is substantially the same as that above described, except that the openings 10 are drilled through the blocks 2, the anchoring portions 14 are of slightly different form and an extra plate or body 20 of insulation is placed between the blocks 2. The plate 20 is preferably of laminated form, similar to the insulating covers 8 in the blocks 2.

The anchoring portion 14, instead of being along the end edges of the member 4, as shown in Fig. 4, are disposed along the longitudinal edges from which they each so project in two directions as to assist in holding the right-angularly related sides of the cover 5 in position.

Modifications and rearrangements of the portions 14 may be made to hold the molded cover 5 in any desired manner.

By my invention, a strain insulator is provided that, besides being of extremely compact, durable and effective character, facilitates and economizes its manufacture and has other features of improvement over insulators heretofore employed.

While I have shown and described particular forms of my invention, changes may be effected therein without departing from the spirit and scope thereof, as set forth in the appended claims.

I claim as my invention:

1. A strain insulator comprising rectangular block elements, including rectangular metal core members and laminated rectangular tubular insulating coverings thereon, disposed in adjacent flat-surface relation, a rectangular tubular metal member surrounding the elements, terminal portions projecting from the core members through said coverings and through said tubular metal member in spaced relation to the latter, and a body of insulation molded in the spaces between the tubular metal member and said terminal portions and about said parts.

2. A strain insulator comprising rectangular block elements, including rectangular metal core members and rectangular tubular insulating coverings thereon, disposed in adjacent flat-surface relation, means for holding the elements to each other and terminal portions projecting from the core members.

3. A strain insulator comprising rectangular block elements, including rectangular metal core members and laminated tubular insulating coverings of rectangular cross section molded thereon, disposed in adjacent flat-surface relation, a tubular metal element of rectangular cross-section surrounding the elements, terminal members including shanks screw-threadably mounted in said core members projecting therefrom through said coverings and through said tubular metal member in spaced relation to the latter, and a body of insulation molded in the spaces between the tubular metal member and said shanks and about said parts.

4. A strain insulator including tubular insulating portions disposed in side-by-side relation transversely to the tension load, anchor members in said tubular portions, a tubular element surrounding said tubular portions in substantially parallel relation thereto and terminal portions projecting through said tubular element from said anchor members in the direction of said load.

5. A strain insulator including tubular insulating portions disposed in side-by-side relation transversely to the tension load, metal anchor members in said tubular portions, a tubular metal element surrounding said tubular insulating portions in substantially parallel relation thereto and metal terminal portions projecting from said anchor members in the direction of said load.

through said tubular insulating portions and through said tubular metal element in insulated relation thereto.

6. An insulator including tubular insulating portions disposed in side-by-side relation, metal anchor members in said tubular portions, a tubular element surrounding said tubular portions in substantially parallel relation thereto and terminal portions projecting through said element from said anchor members transversely to the axis of said tubular element.

7. An insulator including tubular insulating portions disposed in side-by-side relation, a tubular element surrounding said tubular portions in substantially parallel relation thereto and terminal means having anchor portions in said tubular portions and portions extending through said element transversely to the axis thereof.

8. An insulator including tubular insulating portions disposed in side-by-side relation, metal anchor members filling said portions flush with the ends thereof, a tubular metal element surrounding said portions in substantially parallel relation thereto and having transverse wall openings, metal terminal portions of smaller diameter than said openings projecting therethrough from said anchor members and a body of molded insulating material covering the insulator and disposed in said openings about said terminal portions.

9. An insulator including tubular insulating portions disposed in side-by-side relation and having transverse side openings, metal anchor members in said portions having screw-threaded openings opposite said side openings, a tubular metal element surrounding said portions in substantially parallel relation thereto and having transverse wall openings opposite said side and screw-threaded openings and metal terminal members having screw-threaded portions in said screw-threaded openings and portions projecting through said transverse wall openings in spaced relation to said element.

In testimony whereof, I have hereunto subscribed my name this 31st day of March, 1927.

WILLARD H. KEMPTON.
